UNITED STATES PATENT OFFICE.

HENRIETTA C. CLINTON, OF SAN FRANCISCO, CALIFORNIA.

TYPE-WRITER ATTACHMENT.

1,135,769.

Specification of Letters Patent. Patented Apr. 13, 1915.

Application filed April 29, 1914. Serial No. 835,239.

To all whom it may concern:

Be it known that I, HENRIETTA C. CLINTON, a citizen of the United States, residing at San Francisco, in the county of San Francisco and State of California, have invented 5 certain new and useful Improvements in Type-Writer Attachments, of which the following is a specification.

My invention relates to an attachment for 10 typewriters and resides in the provision of improved means for returning the carriage and spacing the paper.

An important object of the invention is 15 to provide an attachment of the character described which is capable of being readily attached to different styles of typewriters.

Another important object of the invention 20 is to provide an attachment of the character described which consists of a pulley to be operatively connected with the carriage of the typewriter and to operate the same and clutch means to be rotated and subsequently rotate the pulley for returning the carriage, that is automatically moved into released or 25 inoperative position, and the pulley permitted free rotation in either direction.

Another important object of the invention 30 is to provide an attachment of the character described which is extremely simple as to construction, reliable and efficient in operation and cheap to manufacture.

The above and additional objects are accomplished by such means as are illustrated in the accompanying drawings, described in 35 the following specification, and then particularly pointed out in the claims which are appended hereto and form a part of this application.

With reference to the drawings, wherein 40 I have illustrated the preferred embodiment of my invention as it is reduced to practice, and throughout the several views of which similar reference numerals designate corresponding parts, Figure 1 is a perspective view showing the attachment as applied to a typewriter, Fig. 2 is a side elevation partly in section of the improved attachment, Fig. 3 is an end elevation of the attachment, Fig. 4 is a vertical sectional view taken on 45 line 4—4 of Fig. 2, particularly illustrating the clutch means and coöperating parts in assembled position, Fig. 5 is a sectional view taken on line 5—5 of Fig. 4 illustrating the tension spring, Fig. 6 is a detail elevation 50 of the operating pulley removed from the clutch means, Fig. 7 is a detail perspective

view of the clutch means, Fig. 8 is a detail perspective view of the collar used in connection with the tension spring, Fig. 9 is a detail perspective view of the shaft for supporting the operating pulley and clutch means, Fig. 10 is a detail perspective view of the collar operated in connection with the spring means for automatically releasing the clutch means, and Fig. 11 is a detail 60 perspective view of the guide bracket for guiding the flexible connection that is pulled when the device is operated.

Referring to the drawings and particularly to Fig. 1, the numeral 1 designates as 70 an entirety a typewriter to which is attached the improved attachment therefor designated 2 as an entirety, this attachment 2 is operatively connected with the carriage designated 3 by means of a suitable flexible 75 means 4. This tape 4 is provided with a suitable eyelet or attaching ring 5 that is fitted over the line spacing lever 6. A pull is given the tape 4 by means of the attachment 2 which will be later described and the 80 carriage 3 is returned to normal position and as will be readily seen the line spacing is provided.

The attachment 2 consists of a U-shaped 85 securing bracket 7 that is provided with a securing screw 8 and suitable nut 9 disposed within its bight portion and arranged to be secured to a typewriter and project laterally therefrom adjacent one side thereof. Bearing surfaces 10 are formed at the free ends 90 of the arms of the U-shaped bracket 7 and coöperate with detachable bearing plates 11 that are secured by screws or other suitable fastening means, in supporting a shaft 12.

Rotatably mounted upon the shaft 12 is an 95 operating pulley 13 that is provided with an enlarged offset hub portion 14 for a purpose which will be later more fully described. One end of the tape 4 is suitably secured to the pulley 13. Formed in the outer end of the enlarged hub portion 14 is a circular recess 15 provided with a slot in its side wall to receive one terminal of a flat expansive spring 16 that is arranged within the recess 15. A flanged cap 17 is fitted upon the outer end of the hub portion 14 to protect the spring 16.

Mounted upon the shaft 12 and interiorly of the hub 14 is a sleeve 18 having a lug 19 formed thereon adjacent one end to which is secured the other terminal of the spring 16. This sleeve 18 is provided adjacent its

- outer end with an inwardly extending recess 20 arranged to receive a lug 21 formed adjacent one terminal of the shaft 12 so that the sleeve 18 and shaft rotate with each other.
- 5 This lug 21 is arranged to be disposed approximately flush with the bearing surface of the sleeve 18.
- As a means for preventing lateral movement of the sleeve 18 relative to the shaft 12
- 10 there has been provided a guide screw 22 that is mounted within the hub 14 and arranged for engagement at its unheaded or inner end with a circular groove 23 formed in the sleeve 18. The operating pulley 13 is
- 15 disposed approximately centrally of the ends of the shaft 12 and the hub 14 and coöperating parts are arranged upon one side of the pulley thus providing the proper space for the positioning and the operation of the
- 20 clutch mechanism which will be later more fully described.

The pulley 13 is provided upon its face opposite to that carrying the enlarged hub portion 14 with an annular recess 24 arranged about a cylindrical clutch member 25 which communicates at its inner end with the hub 14 and may be formed integral therewith and is internally screw threaded. A pin 26 is arranged in the recess 24 and is

30 for a purpose which will be later described.

The clutch mechanism consists mainly of a casting designated 27 as an entirety and illustrated in detail in Fig. 7 in the drawings. The casting 27 is shaped generally in the cylindrical form and is constructed in the nature of a spool with a central bore 28 to provide for the mounting of the casting 27 upon the shaft 12. The casting 27 consists of a body portion 29 provided with spaced annular flanges 30 which form in combination with the body portion a drum to which is secured one end of a tape or suitable flexible element 31, the tape is adapted to be wound upon the clutch mechanism

45 when the device is being operated after a manner which will be later more fully described.

One of the plates 30 is provided at a point spaced from its periphery with a laterally extending circular flange 31^a which forms a spring receiving chamber 32 arranged to receive a flat expansive spring 33 similar to the one 16 previously described. The flange 31 is slotted as at 34 to receive one terminal of the spring 33. Loosely mounted upon the shaft 12 and extending within the chamber 32 is a cylindrical sleeve 35 that is illustrated in detail in Fig. 10 in the drawings. The end of this sleeve 35 that is extended within the chamber 32 is provided with a lug 36 to which is secured the other terminal of the spring 33. The outer end of the sleeve 35 is provided with diametrically opposed inwardly extending recesses 37 adapted to receive a suitable tool for adjustment after the

manner which will be later described. The outer end of this sleeve 35 is clamped by the bearing elements 10 and 11 and houses the adjacent end of the shaft 12.

The detachable bearing plate 11 may be 70 secured sufficiently tight to hold the sleeve 35 against rotation with the shaft 12. It will thus be seen that a suitable tool may be placed in engagement with the recesses 37 and the sleeve 35 rotated until the desired 75 tension of the spring 33 is provided whereupon the detachable bearing plate 11 may be screwed tightly and the desired spring action maintained. A flanged centrally apertured cap 38 is mounted upon the flange 31 and completely houses the spring 33, as will be clearly seen with reference to Fig. 4 in the drawings. The body portion 29 of the casting 27 is extended beyond the other flange or plate 30 and is externally threaded to 80 fit within the internally screw threaded clutch member 25. The innermost flange 30 is provided with a circular laterally extending flange 39 that is provided with a cam edge 40 arranged to provide a stop shoulder 90 41. This flange 39 is arranged to fit within the annular recess 24 and rotate therein, while the screw threaded body portion 29 of the clutch mechanism is being turned into the internally screw threaded clutch member 25 as will be later more fully described.

A guide attachment for the tape 4 designated 42 is secured to some suitable part of the typewriter 1 and provided with an apertured portion 43 through which is inserted the tape 4. This guide 42 is preferably arranged adjacent the end of the typewriter to which the attachment 2 is secured. A guide for the tape or flexible element 31 designated 44 as an entirety and particularly illustrated in Fig. 11 consists of a bar 45 having one end bent at right angles to the body portion and designated 46 and secured to the right portion of the U-shaped bracket 7 in any suitable manner. The bar 44 is arranged to extend laterally from the typewriter 1 and beneath the casting 27 forming a part of the clutch mechanism and is provided at its outer end with oppositely arranged hook shaped portions 47 arranged to receive the flexible element 31. The flexible element or tape 31 is designed to be pulled downwardly by some suitable means not shown, to be operated by the person operating the typewriter.

The operation of the attachment may be briefly described as follows:—Assuming that the carriage 3 of the typewriter 1 is in its normal position, the operator in pressing the typewriter keys causes the carriage 2 to move to the left, this being the operation of the standard typewriter. Assuming that the attachment 2 is secured after the manner described to the typewriter 1, when the carriage 3 moves to the left, the tape 4 is un-

wound from the pulley 13 which is rotated in a counter clockwise direction against the action of the spring 16 causing the spring to wind up. When the carriage 3 has 5 reached its outermost extended position and the operator is desirous of returning it to normal position, the flexible element or tape 31 is pulled downwardly causing the casting 27 of the clutch mechanism to be rotated in 10 a clockwise direction and the screw threaded body portion 29 thereof to move into threaded engagement with the clutch member 25. This action continues until the stop shoulder 41 engages the pin 26 in the annular recess 24 of the pulley 13 at which time the rotary movement of the casting 27 of the clutching mechanism imparts a similar movement to the pulley 13. Thus it will be seen that the carriage 3 is returned to its 15 normal position and the line spacing provided as the pull communicated the tape 4 that is attached to the line spacing lever 6 is sufficient to first space the line and then pull the carriage 3 to its normal position. When 20 the flexible element 31 is being pulled downwardly it is unwinding from the casing 27 of the clutching mechanism and rotating against the action of the spring 33 which is being wound up. Immediately upon the release 25 of the flexible element 31 the spring 33 unwinds and a counter clockwise rotation is imparted the casting 27 of the clutch mechanism thus causing it to move out of operative engagement with the pulley 13 and 30 clutch member 25 carried thereon. It will thus be seen that the pulley 13 is free to rotate when the clutch mechanism is moved into inoperative position after the manner described. The spring 16 serves to provide 35 for the desired tension of the tape 4 when the carriage is returned by hand in the usual way and it will be noted that the ordinary operation of the typewriter is not interfered with by the application of the attachment 40 hereinbefore described and illustrated in the accompanying drawings. It will also be noted that any suitable means may be employed for exerting a downward pull on the flexible element 31 and in this connection it 45 has not been thought necessary to specifically describe or illustrate certain means which might be used successfully.

One of the most essential points of the invention is the fact that the attachment 50 may be readily attached to typewriters of all kinds, in some instances necessitating only slight changes of construction and arrangement. It will be also noted that there has been provided an automatic clutch releasing mechanism which is of a novel construction and arrangement and permits the construction of an efficient and extremely reliable device for returning the typewriter carriage and automatically spacing a line.

65 In reduction to practice, I have found

that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

What is claimed is:—

1. An attachment for typewriters comprising a bracket, a shaft mounted in the bracket, a pulley rotatably mounted upon said shaft, a flexible element secured to said pulley and to the carriage of said typewriter arranged to wind on said pulley, an internally screw threaded cylindrical clutch member carried by said pulley, a second clutch member rotatably journaled upon said shaft, a screw threaded portion on said second clutch member coöperating with the first clutch member, and means for moving said second clutch member into inoperative position whereby said pulley is free to rotate.

2. A typewriter attachment comprising a supporting bracket, a shaft mounted in said bracket, a pulley rotatably mounted upon said shaft and operatively connected with the carriage of said typewriter, said pulley having an enlarged hub portion arranged upon one side thereof, said hub portion being recessed to provide a spring chamber, a spring mounted within said chamber and arranged above said shaft, a sleeve mounted upon said shaft and extending into said chamber, said sleeve having a recess adjacent one end, a lug formed on said shaft and extending into said recess, said spring being secured at its terminals to said hub and the sleeve, said pulley being provided upon its face opposite to the hub portion with a recess, a cylindrical internally screw threaded clutch member carried centrally within the recess, a stop pin arranged within the recess, a clutch member rotatably mounted upon said shaft coöperating with said first named clutch member and stop pins to rotate said pulley to return said carriage and means for automatically moving said second clutch means into inoperative position whereby the pulley is free to rotate in either direction.

3. A typewriter attachment consisting of a shaft, means to support the shaft, a pulley mounted upon said shaft and operatively connected with the carriage of said typewriter, said pulley having a hub portion arranged thereon, said hub portion being formed with a spring chamber, a spring mounted within said chamber, a sleeve mounted on said shaft and extending into said chamber, said sleeve having a recess adjacent to one end, means carried on said

shaft to extend into the recess, said spring being secured at its terminals to the hub and sleeve, said pulley being provided upon its face opposite to the hub portion with a
5 recess, a cylindrical clutch member carried within the recess, a stop pin within the recess, a clutch member mounted upon said shaft rotatably and coöperating with said first named clutch member and stop pin to
10 rotate said pulley to return said carriage

and means for automatically moving the clutch member into inoperative position whereby the pulley is free to rotate in either direction.

In testimony whereof I affix my signature 15
in presence of two witnesses.

HENRIETTA C. CLINTON.
